MEANS AND METHOD OF ORIENTING DEFLECTING TOOLS IN WELLS

Clyde I. Stokenbury, Long Beach, Calif., assignor to Eastman Oil Well Survey Company, Dallas, Tex., a corporation of Delaware

Application November 28, 1936, Serial No. 113,134

7 Claims. (Cl. 33—72)

The invention relates to a means and method of moving a string of pipe in a well bore and has particular application in the positioning of deflecting tools and other instruments in well bores where it is desired to know the orientation of the tool or its azimuth.

It will be understood that as a string of pipe is moved in the well bore where the pipe is made up of pipe sections that the pipe sections are connected and disconnected in stages so that their movement is effected by a step by step operation until the deflecting tool has either been moved into or out of the well bore or to some predetermined elevation.

15 It is one of the objects of the invention to provide a simple and economical apparatus which can be readily attached to the pipe sections in order to carry some predetermined point on the pipe along the periphery of the pipe so that it will be known at all times where the original point is with respect to the aligned point which is being carried along the pipe as it moves.

Another object of the invention is to transfer a predetermined point along the length of the sections of pipe as they are connected or disconnected during the movement of the pipe by transferring this point along a plane.

Another object of the invention is to provide an apparatus for aligning pipe sections which includes a target and a sighting device which are to be alternately connected and disconnected to the successive pipe sections in order to carry a point along in the plane of the pipe as it is assembled or disassembled.

35 Another object is to provide an apparatus which may be used by only one operator in the derrick because the person on the derrick floor need only insert and remove the target and release the clamp while all of the sighting is done by the derrick man.

Another object of the invention is to provide a pair of clamping members which can be alternately attached to the pipe so that a sighting device and a target may be carried along the pipe in a known relation to a predetermined point on the periphery of the pipe.

Another object of the invention is to provide a clamp member having a means thereon to receive either a sighting device or a target which can be alternately attached thereto in order to carry a point in alignment along a string of pipe.

Other and further objects of the invention will be readily apparent when the following description is considered in connection with the 55 accompanying drawing, wherein:

Fig. 1 is a diagrammatic arrangement of a string of pipe being lowered into the well bore and showing the manner by which the alignment of pipe is transferred from stage to stage during the movement of the pipe.

Fig. 2 is a plan view looking down on one of the clamping members which is supporting a telescope or sighting device by which the point of alignment is transferred.

Fig. 3 shows a transverse section of the clamping device shown in Fig. 2 but carrying a target member which can be alternately positioned therein with the sighting device in order to transfer the point of alignment along the string of pipe.

In Fig. 1 a derrick is indicated generally at 2 and is provided with the usual crown block 3, the traveling block 4, and the operating cable 5. Suspended on the traveling block, are the elevators 6 which serve to support the string of pipe 7 which is to be moved in the well bore and whose position is to be aligned so as to ascertain its relative azimuth at any time during the movement in the hole.

It is to be understood that the means and method of the present invention may be applied in practice in various forms but the invention concerns itself with aligning the adjacent pipe sections so that some predetermined point on the periphery of the pipe may be carried along the pipe so that the plane along which the predetermined point has been moved is known on the surface at all times.

The drawings of Figs. 1, 2, and 3 are all diagrammatic, and for purposes of illustration present a deflecting tool 10 as being moved into the top of the well bore after having been connected to a section of pipe 11. It will be seen that this deflecting tool 10 has a deflecting face 12 whose position in the well bore after it reaches the desired elevation is to be ascertained by carrying along the pipe a point which, for purposes of illustration, will be taken as the normal or perpendicular to this deflecting face 12. The normal has been indicated by the line of a target 14 which extends perpendicular to the face 12. Any other point may be selected arbitrarily, however.

The number of stages which are required to move the pipe in the hole will of course depend upon the length of the pipe sections, the distance the string of pipe is to be moved, and the height of the derrick 2. In the present instance the derrick is shown as being of a height to accommodate more than the length of one pipe section such as 11 and a second pipe section 15 is shown

as connected thereto with the upper end of the section 15 being supported in the elevator 6. Any desired number of pipe sections may be made up together before they are attached to the string of pipe being lowered into the well bore. In practice, these pipe sections are known as singles, doubles, thruples or fourbles, depending upon how many sections are made up before they are attached in the pipe string.

In carrying out the invention a plurality of clamping members 20 may be used to support the target 14 and the sighting device. To carry the selected point along the pipe one of the clamping members 20 is placed about the upper end of the pipe section which is uppermost in the stage in the derrick and this clamp is then moved circumferentially about the pipe until the sighting member 21 can be trained upon the line 14 as a target. The target may be fixed initially to the tool 10 by a clamp 20 or otherwise. When it has been so circumferentially adjusted the set screw 22 is then adjusted so as to securely fix the clamping member to the pipe in this position.

It seems obvious therefore that the sighting device 21, and in fact the entire clamp 20, is now positioned on the pipe so that it is in alignment with the target 14.

The sighting device 21 is carried in a socket 24 which is formed in the body 23 of the clamping device, as clearly seen in Fig. 2, the body 23 being made up of a circular section which is arranged to receive the periphery of the pipe 15. The point 25 of the clamping member 22 will bite into the pipe so as to draw the shoulders 26 and 27 firmly against the opposite side of the pipe. These shoulders 26 and 27 will be of sufficient length so that the clamping member 20 will be properly aligned along the pipe in order to support the sighting device 21.

The sighting device may be in the form of a telescope by which an accurate sight can be taken along a plane radially of the pipe. The sighting device is supported in a yoke 30 upon which it may be pivoted as at 31 so that a cross hair in the sighting device will be aligned with the line 14 of the target to indicate that they are in the same circumferential position. The yoke 30 in turn carries a shank 33 which is arranged to be positioned in the socket 24. It is to be understood that the shank 33 can only be positioned in the socket 24 in an exact position with respect to the center line 35 which passes through the point of the set screw 25, the socket 24 and the center of the yoke 30. While the drawing shows this position as radial it is to be understood that it can be offset or otherwise positioned. In this manner, whenever a sight is taken through the telescope 21 the line of sight will be along a plane which is parallel to the axis of the pipe 15 and in alignment with any predetermined point such as the point 36 on the periphery of the pipe which will move along that plane.

When the clamp 20 has been suitably positioned upon the pipe and the alignment sight taken through the telescope 21 then the target 14 can be removed from the lower portion of the pipe and the pipe moved downwardly in the well bore, it being understood that the present description is given in connection with the lowering of the string of pipe, the operation being reversed in event the pipe is being raised.

As the pipe is to be lowered the telescope 21 will be removed from its socket but the clamp 20 will remain in its predetermined fixed position on the pipe. As the lowering operation occurs of

course the clamp 20 will move down to its position close to the floor of the derrick. Another stage of pipe sections will then be added to the top of the section 15 and another clamping member identical with the member 20 will be positioned about the upper end of this new stage of pipe sections and the telescope 21 having been retained in the upper part of the derrick by the derrick man is now being positioned in the socket 24 in this second clamp which is being positioned about the upper end of the pipe. In the meantime the target 14 will be positioned in the first clamp which has been lowered to the derrick floor. The target 14 carries a shank 33 which is identically the same as the shank 33 to which 15 yoke 30 of the sighting device 21 is attached. In other words, the sighting device 21 and the target 14 are interchangeable in the clamp so that they can be alternately arranged therein in order to carry the point in alignment along a plane on 20 the pipe.

When the parts are in this position the sighting device will be moved circumferentially into alignment with the target which is now carried by the first clamp which previously carried the sighting 25 device, whereas the sighting device is now carried by the second clamp. This second clamp is now adjusted circumferentially around the pipe until the sighting device is trained directly on the target 14 and it is then fixed in position. It should 30 be noted that the sighting device need not be exactly vertical but can sight along the line 14 in the plane thereof. This permits the speedy location of the apparatus. The lowering movement of the pipe is then continued and another stage 35 of pipe sections is added with the target again being removed from its clamp and the telescope being removed from its clamp so that what was the upper clamp now moves down to the lower position and the upper clamp moved upwardly to 40 be attached to the pipe the second time. This alternation of clamps and the sighting and target members is continued until the pipe string arrives at the desired elevation in the well bore. At this time the last clamp which has been affixed 45 to the pipe indicates exactly to the operator the circumferential position of the plane along which the predetermined point on the periphery of the pipe has been moved during the lowering movement. In other words, in the example illustrated 50 here the position of this last clamp will indicate the normal to the deflecting face 12 which was selected as being the point which would be carried along in alignment.

If the deflecting face 12 is then to be set at any 55 predetermined position of the compass the entire pipe string can be rotated through the desired arc so as to move this face to its desired position so that the pipe is in this manner oriented in the hole with respect to any desired location and 60 its azimuth is therefore known.

The present means and method is of particular advantage because it is not necessary to spend the time to sight upon a target at a distance which is difficult at night and during 65 unsettled weather conditions, neither does it rely upon any particular scale, algebraic computation, angular summation, or any zero object other than the predetermined point which has been selected as being the point which will move 70 in alignment during the movement of the pipe.

The lack of mathematical calculations on the floor of the derrick with its noise and confusion are of material advantage and tend toward a greater accuracy. The apparatus used is simple 75

and economical and can be manipulated by a single operator in the derrick who does the sighting. The use of two telescopes is eliminated and if desired a two-way telephone or sound equipment may be placed in the derrick for conversation between the workers.

It is to be understood that the clamp, the sighting device and the target may take any particular form or construction because those illustrated in the drawing are merely diagrammatic.

What is claimed is:

1. An apparatus to orient a string of pipe being moved in a bore hole comprising a pair of clamp members, a socket in each member, a sighting device, a target, and means on each, said sighting device and said target so that they may be disposed in said sockets so that by sighting said device upon said target the two clamp members may be alternately attached to the pipe so that the azimuth of the original position of the target can be ascertained as the sections of pipe are moved longitudinally.

2. In an apparatus for use with a plurality of sections of pipe to be progressively connected or disconnected and moved longitudinally of a bore hole, a means to transfer an original plane of the string of pipe which is being moved which comprises a pair of members adapted to be alternately fixed to the pipe, and means adapted to be removably positioned on said members so that each member when fixed to the pipe can be aligned with the alternate member which has preceded it by sighting along the pipe, said means comprising a sighting device and target therefor.

3. A clamp member for aligning pipe sections comprising a body, means thereon to clamp said body to the pipe, means also on said body to receive an aligning member so that said clamp means may be operated when the body is aligned, and a target device to be disposed in said last means.

4. In the art of orienting a string of pipe into or out of a well bore which comprises the steps of fixing a target in any desired relative angular position upon the string of pipe, alternately sighting along the pipe from a position on the

pipe upon the target, and then reestablishing the position of the target at another position longitudinally along the pipe from which the sight was taken so as to carry the relative angular position of the target along the pipe above the surface. 5

5. The art of transferring along a string of pipe that is being lowered into or removed from a well bore a plane which has a definite fixed position relative to the string of pipe, which comprises alternately fixing a target and a sighting 10 device upon the pipe, sighting with the device from a point on the pipe along the pipe so as to reestablish the target on the pipe at each stage in the same vertical plane with respect to the pipe so that at any stage it is known that the 15 position of the target represents the angular position of the plane with respect to the pipe.

6. A method of orienting a string of pipe into or out of a well bore regardless of any rotation thereof during the raising or lowering thereof 20 which comprises the steps of sighting along the pipe from a position on the pipe to a predetermined point also on the pipe so as to position the sighting device upon the pipe in a predetermined plane, and thereafter again sighting along the 25 pipe to transfer the plane to another longitudinally spaced position on the pipe.

7. A method of orienting a deflecting tool which is to be positioned in a bore hole by an operating string of pipe which pipe is made up of 30 sections to be coupled and uncoupled which method comprises the steps of sighting from a point on the pipe along a plane which is normal to the deflecting face of the tool, establishing the sighting device on the pipe in such plane, and 35 thereafter reestablishing the circumferential position of such plane periodically along the pipe as it is moved by sighting along such plane from one point on the pipe to another point on the pipe so that when the tool arrives at the desired 40 elevation the last established point on the pipe at the surface will indicate the plane of the normal to the face of the deflecting tool, and rotating the pipe as a whole to position the deflecting face in the desired circumferential position. 45
